 Donald W. Robertson

Application March 27, 1937, Serial No. 133,353

6 Claims. (Cl. 155—38)

This invention relates to chairs; more particularly, to chairs of the type intended for the use of children at the table. It has especial reference to chairs which are adjustable to the requirements of growing children, and which are adapted for the use of children throughout the period beginning with babyhood and extending up to the age at which the child is ready to use comfortably a chair designed for adults.

It is an object of the present invention to provide a chair of the class described which can be so adjusted as to assure good table posture for the child throughout his growing years. It is a further object to provide a chair having a unitary seat, back and arm structure which can be raised or lowered by a rapid, simple, adjustment.

A more particular object is to provide a combined high-chair and junior chair wherein the seat portion can be raised or lowered without folding or telescoping the legs. A further object is to provide a chair of this class wherein the seat, upon being lowered, is adapted to pass below the plane of the upper ends of the legs whereby the latter may be utilized to strengthen the chair as the child increases in stature.

A specific object is to provide an adjustable high-chair wherein the upper ends of the legs are shielded for all positions of the seat, and wherein in the upper end of the leg structure is utilized as a guiding and positioning means for the seat during the vertical adjustment of the latter. Another specific object is to provide a chair in which the leg structure is related to the arm and back structure in such a way as to constitute a part thereof for lowered positions of the seat, thus to disguise the adjustment means and improve the appearance of the chair.

Other objects and advantages of my invention will appear as the description proceeds.

In the drawings, Fig. 1 is a side elevational view of a chair representing a preferred embodiment of my invention. In this view the seat is shown in its uppermost position.

Fig. 2 is a view similar to Fig. 1, but showing the seat structure in its lowermost position. In this view the lower part of the leg structure has been omitted to avoid unnecessary duplication of the disclosure of Fig. 1.

Fig. 3 is a front elevational view of the upper part of the structure shown in Fig. 1; and Fig. 4 is a horizontal sectional view taken on the line IV—IV of Fig. 3.

Figures 5 and 6 show my preferred form of seat latch mechanism, Fig. 5 being a bottom plan view of the seat with the latch mechanism ap-

plied thereto, and Fig. 6 being a vertical sectional view taken on the line VI—VI of Fig. 5. The scale of Fig. 5 is enlarged over that of Figs. 1 to 3 inclusive, and the scale of Fig. 6 is greater than that of Fig. 5.

Referring first to Figs. 1 to 4 inclusive, and more particularly to Fig. 1, I have illustrated my invention by a chair comprising a unitary seat structure embodying a seat 1, back 2 and arms 3, and a unitary leg structure comprising legs 4 and rungs 5. The upper ends of the legs 4 pass through apertures 6 in the seat 1, providing a vertical sliding engagement between the seat structure and the leg structure. The under sides of the arms 3 are preferably recessed at 7 to receive the upper ends of the front pair of legs when the seat structure is lowered, as shown in Fig. 2. I also prefer to provide recesses 8 in the lower edge of the back 2 to receive the upper ends of the back pair of legs when the seat structure is in the lowered position shown in Fig. 2.

A feature of the preferred embodiment as illustrated is the greater length of the front legs than the back legs. This permits the upper ends of the front legs to extend above the plane of the seat even when the seat is in its uppermost position, as shown at 9 in Fig. 1. Here the upper ends are flush with the top surface of the arm braces 10. With this arrangement a number of advantages are secured: first, the engagement of the extensions 9 with the arm braces 10 serves to strengthen the connection between the seat and leg structures for all positions of the seat; second, the slideable engagement of each front leg 4 with both the seat 1 and the brace 10 rigidly attached thereto by the balusters 11 provides a guiding sleeve of an effective length equal to the distance between the point of engagement of the extension 9 with brace 10 and that of the leg 4 with seat 1, which guiding sleeve serves to keep the seat assembly and leg assembly in alignment during the operations of raising and lowering of the seat assembly; third, the extensions 9 serve to bring the tops of the front legs up far enough to reach the arms 3 when the seat is in its lowermost position whereby in that position the tops of these legs as well as of the back legs are shielded, and the front legs become a part of the baluster design of the arms.

The upper portions of the legs 4 are parallel, as seen best in Fig. 1, but their lower portions preferably are flared outwardly to provide a broad, safe, base. The parallel upper portions make possible a smooth sliding engagement with the seat.

After the seat structure and leg structure have been assembled, a stop pin 12, or other limit stop, is inserted at the top of each leg. The projecting portions of these pins nest into corresponding recesses in the upper surfaces of the seat 1 and arm braces 18 when the seat is in its uppermost position (Fig. 1), and slide freely in grooves in the sides of recesses 7 and 8 in the under sides of arms 3 and lower edge of the back 2, respectively, when the seat approaches its lowermost position. When the seat reaches its lowermost position (Fig. 2), it rests on the upper pair of rungs 5, while the back 2 is supported by the tops of the back pair of legs and the arms 3 are supported by the tops of the extensions 9 of the front pair of legs. This provides an extremely rigid assembly when the seat has been placed in its lowermost position which is the time when it is most needed, i. e., when the seat has been adjusted to the proper height for a child of five to seven years.

Any suitable latching means may be provided for locking the seat in its upper, lower and intermediate positions. Figs. 5 and 6 illustrate a simple and effective mechanism for this purpose. It is of advantage to provide a latch at all four legs, but to so arrange them that they may be operated together. In the arrangement of Figs. 5 and 6, the latch mechanism is mounted on the underside of the seat 1. In this embodiment, the latch mechanism consists of rods or bolt members 13 and suitable actuating means therefor. Each bolt member 13 is arranged to be projected into a position in which its outer end lies directly below the corresponding aperture 6 in the seat 1. Thus when the seat structure is assembled with the leg structure the outer end of each bolt 13 is adapted to enter a locking recess 14 (Fig. 3) formed in the corresponding leg 4. Each leg is provided with the desired number of such locking recesses 14 at various heights so that the seat can be locked in position at the desired heights. I prefer to position these locking recesses 14 at the proper heights to lock the seat in the positions shown in Figs. 1 and 2, and in at least one intermediate position.

The inner end of each bolt member 13 is pivotally secured to the actuating handle 15. A simple form of such pivotal attachment is shown in Fig. 6, the end of the bolt member 13 being bent over at a right angle and passing through a hole in the handle 15, as at 16, and secured by a cotter pin 17. The handle 15 is formed conveniently from sheet metal and preferably is provided with a depending flange 18 to reinforce it against bending, furnish a convenient hand grip, and to engage a spring locking clip 19. The locking clip 19 provides a stop for the handle and also serves to hold it in locked position. The base of the handle 15 is centrally apertured, and through this aperture passes a screw 20, or other attaching means, for pivotally securing the handle 15 to the underside of the seat 1. Around this central aperture are arranged the aforesaid holes for receiving the inner ends 16 of the bolt members 13. The spacing of these holes is such as to permit the use of bolt members of equal lengths and to produce an equal retracting movement of all the bolt members for a given rotation of the handle 15 in the direction of the arrow a. Guides 21 are fastened to the seat 1 near the apertures 6 therein, the bolt members 13 being arranged to reciprocate in these guides upon movement of the actuating handle 15. If desired, the bolt members 13 may be concealed in recesses in the underside

of the seat 1. Recesses 22 and 23 are formed in the underside of the seat 1 to receive the ends 16 and allow for the oscillatory movement thereof. Recess 23 is made of sufficient length to accommodate a spring 24 which is concealed above one of the bolt members 13. One end of the spring 24 is fastened to the seat 1, as by a screw 25, while its other end is secured to the inner end of the same bolt member 13. The spring is placed under an initial tension sufficient to insure a clockwise rotation of the handle 15 as viewed in Fig. 5, constantly urging the bolt members 13 into the locking position there shown. The spring 24 operates with the spring locking clip 19 in maintaining the locking mechanism in its fully locked position.

Adjustment of the height of the seat 1, when equipped with a locking mechanism such as described hereinabove, is effected by reaching under the back of the seat with one hand, moving the handle 15 in the direction of the arrow a, lowering the seat into the desired position, then releasing the handle or moving it back into engagement with the spring clip 18. If the seat is not at the proper height for the bolts 13 to engage locking recesses 14 in the legs 4, it is raised or lowered slightly until the bolts 13 slip into the nearest set of locking recesses. It is to be noted that by reason of the provision of the stop pins 12 at the top of the legs 4, the bolts 13 are easily brought into alignment with the uppermost set of locking recesses 14. In like manner, when the seat reaches its lowermost position, the engagement of the seat 1 with the upper pair of rungs 5, of the back 2 with the tops of the back pair of legs, and of the arms 3 with the tops of the extensions 9 of the front pair of legs, brings the seat into exact alignment with the lowermost set of locking recesses 14.

A foot rest 26 is adjustably secured to the front pair of legs 4, as by means of the bolts 27. Lower positions of this foot rest are indicated by the dot-dash lines 26' and 26''. If desired, the foot rest may be secured to the seat structure so as to be raised and lowered therewith, or may be attached to both the seat and leg structures by a linkage which causes the foot rest to be raised or lowered automatically and also to increase automatically the distance between the seat and the foot rest for successively lower seat positions.

A food tray may be pivotally attached to the chair in the usual manner, or adjustably secured to the arms thereof.

The principal objects and advantages of my invention can be attained with chair structures quite different in form and general appearance from that which has been selected for purposes of illustration. The teaching of this specification will suggest many such modifications to those skilled in the art. For example, the guiding sleeve which has been described as serving to keep the seat assembly and leg assembly in alignment during the operations of raising and lowering of the seat assembly may, if desired, be made in the form of a continuous sleeve extending from the seat 1 to the arm 3; or the arms 3 may be provided with depending portions at their forward ends, these depending portions being recessed or apertured to receive the upper ends of legs 4 with their extensions 9. Such alternatives possess the advantages enumerated of strengthening the connection between the seat and leg structures for all positions of the seat, providing a guiding sleeve for preserving alignment, and shielding the upper ends of the legs. These

modifications, as well as all other modifications which may be made, are intended to be included within the scope of the claims.

I claim:

- 5 1. A chair comprising a unitary seat structure embodying a seat, back and arms, and a unitary leg structure, said seat structure having a slide-
able engagement with said leg structure to per-
mit raising and lowering of said seat structure,
10 and said back and arms arranged to rest directly
upon the upper ends of the legs when the seat
structure is in lowermost position.
- 15 2. A chair comprising legs and a unitary seat
structure embodying a seat, back and arms, said
seat structure having a slideable engagement with
said legs to permit raising and lowering of said
seat structure, said arms having recesses in their
20 under sides adapted to receive the upper ends
of a pair of said legs when the seat structure
is lowered.
- 25 3. A chair comprising legs and unitary seat
structure embodying a seat, back and arms, said
seat structure having a slideable engagement with
said legs to permit raising and lowering of said
seat structure, said back having recesses in its
lower edge adapted to receive the upper ends
25 of a pair of said legs when the seat structure is
lowered.

4. A chair comprising legs and a unitary seat structure embodying a seat, back and arms, said seat structure having a slideable engagement with said legs to permit raising and lowering of said seat structure, said arms and back having re-
cesses in their under sides and lower edge re-
spectively, said recesses adapted to receive the
upper ends of said legs when the seat structure
is lowered.

5 5. A chair comprising legs joined to form an 10 integral leg structure, and a unitary seat struc-
ture embodying a seat, back and arms, said seat
structure having a slideable engagement with said
leg structure to permit raising and lowering of
15 said seat structure, and said arms having re-
cesses in their under sides adapted to receive
the upper ends of a pair of said legs.

6. A chair comprising legs and a unitary seat structure embodying a seat, back, arms and arm supports, said seat structure having a direct slide-
able engagement with said legs to permit raising
and lowering of said seat structure, said arms
having portions which rest directly upon the
upper ends of the legs when the seat structure
is lowered, and said arm supports having por-
20 tions which surround portions of the legs for a
plurality of positions of the seat structure.

DONALD W. ROBERTSON.
